UNITED STATES PATENT OFFICE.

JOHN F. WILMOT, OF CHICAGO, ILLINOIS, ASSIGNOR TO A. H. ANDREWS & COMPANY, OF SAME PLACE.

DESIGN FOR A HANDLE FOR FURNITURE.

SPECIFICATION forming part of Design No. 22,161, dated January 24, 1893.

Application filed December 16, 1892. Serial No. 455,394. Term of patent 7 years.

To all whom it may concern:

Be it known that I, JOHN F. WILMOT, a citizen of the United States, residing at Chicago, in the county of Cook and State of Illinois, have invented and produced a new and original Design for Handles for Furniture, of which the following is a specification, reference being had to the accompanying drawing, in which the figure is a top or plan view showing the handle and its supports.

The leading feature of my design consists in a handle elliptical in longitudinal section and circular in cross section. The surface of the handle is beaded, presenting the appear-

ance of a number of rings secured together and gradually diminishing in diameter from the center toward the ends. 15

In the drawing,—*a* indicates the handle, *b* a bar upon which the handle is mounted, and *c c'* supports which carry the bar *b*. 20

I claim,—

The design for a handle, substantially as shown and described.

JOHN F. WILMOT.
